UNITED STATES PATENT OFFICE,

GEORGE S. COLEMAN, OF WASHINGTON, DISTRICT OF COLUMBIA.

BASE-BALL SCORE-BOARD.

1,069,920.

Specification of Letters Patent. Patented Aug. 12, 1913.

Application filed November 25, 1912. Serial No. 733,401.

To all whom it may concern:

Be it known that I, GEORGE S. COLEMAN, citizen of the United States, residing at Washington, in the District of Columbia, have invented certain new and useful Improvements in Base-Ball Score-Boards, of which the following is a specification.

My invention relates to base-ball score-boards.

One of the objects of my invention is to provide a base-ball score-board whereon the various figures representing the players of the two teams may be shown in action while going through various movements on the field and while executing various plays of the game, as for instance running after a batted ball and receiving and throwing the same, running to the various bases, the practising of a pitcher or catcher or both preliminary to being put into the game, the walking of a player from the bench, picking up a bat and assuming a position in the batter's box, the actions of the coaches while coaching, and various other movements and plays such as usually occur on a base-ball field during a game.

A further object of my invention is to provide a base-ball score-board whereon a batted or thrown ball will be represented in motion.

A further object of my invention is to provide a base-ball score-board which shall be of extremely simple construction, economical to manufacture, and which is adapted to intensify the interest of the spectators during the reproduction of a game.

Other objects of my invention will be apparent from the description hereinafter when taken in connection with the accompanying drawings.

The invention consists in the novel construction, arrangement and combinations of parts as hereinafter fully described, illustrated in the drawings and pointed out specifically in the appended claims.

In the drawings: Figure 1 is a front view of the score-board. Fig. 2 is a rear view thereof. Fig. 3 is a vertical sectional view of portions of the front and rear boards and one of the light boxes. Fig. 4 is an elevation of the parts shown in Fig. 3 looking in the direction of the arrow. Fig. 5 is a sectional view showing a portion of a light box and a colored plate arranged in front of the ground glass plate. Figs. 6 and 7 are detail

views showing slots in the rear board and notches of different shapes. Fig. 8 is a sectional view of the rear board showing one of the openings for the insertion of a light box and a curtain to close said opening. Fig. 9 is a front view of a light box. Fig. 10 is an elevation of a portion of the rear board, showing a player in different positions and a portion of one of the slots along which travels a light box used for indicating a ball.

My improved score-board is intended to graphically reproduce a base-ball game played at some place more or less remote from where the board is located, as in a distant city, the various plays of the game being received telegraphically and such plays being then reproduced on the score-board by the operators provided for that purpose.

In carrying out my invention I provide a board 1 the outer face 2 of which is presented to the view of the spectators and upon which board a base-ball game is adapted to be reproduced. The board 1 may have any suitable dimensions, but sufficiently large to enable the various plays to be distinctly seen by the spectators located at a greater or less distance in front of the board. The board may be made of any suitable material but preferably a material which will be cheap and light in weight, as wood, paper-board, etc., and it may be of any desired thickness but preferably not more than one-half an inch. Upon the outer face 2 of the board there is represented a base-ball diamond, field, grandstand, etc., so as to make the board resemble closely a regular base-ball grounds, and the various representations being appropriately colored in practice.

Upon the board there are representations of the various players of the team in the field, as 3, 4, 5, 6, 7, 8, 9, 10, and 11, the players, as 12, of the team at the bat, the coaches as 13, the umpires, as 14, etc., all being shown as occupying positions corresponding closely to the positions assumed in a regular game.

For the purpose of intensifying the interest of the spectators and to make the various plays of the game resemble as closely as possible the actual plays as they occur in the game, I provide representations of the various players in positions assumed while making certain movements or executing plays, as for instance I show by a succession of representations a batter, as 15, 110

running from the home base to first base; also base runners, as 16, 17, 18 running between various bases, the fielders, as 9, 10, 11 running after a batted ball and receiving and throwing same, a pitcher in the act of delivering a ball, a player, as 12 walking from the players' bench toward the home base, picking up a bat and assuming a batting position, and also walking from the home base back to the bench after being declared out, etc. etc.

By providing a succession of representations on a transparent or semi-transparent material to represent the different positions which a player would assume approximately while making a play, and passing an illuminant at the back of such representations in succession, it will be understood that I obtain a moving-picture effect which serves to greatly increase the interest of the spectators in each play as it is made.

The various representations shown on the board must be transparent or semi-transparent in order to permit light from an illuminant in rear thereof to pass through same, and for attaining this result any suitable material, as glass, mica, or the like may be used. I preferably use mica on account of its lightness and cheapness, and I use sheets 30 thereof, one for each representation (only one sheet being shown) glued or otherwise secured to the outer face 2 of the board 1, the latter being cut out to form the outlines of the players, and the sheets of mica being arranged immediately over the said cut-out portions. The mica sheets could be arranged upon the rear face of the board 1, but I preferably arrange them upon the outer face thereof. Instead of cutting out the board 1 to form the outlines of the players, the mica sheets might be colored so as to leave transparent portions having the outlines of the players. In fact, I do not wish to be restricted to any specific construction whereby it is possible to obtain the effect of an outlined figure on the board.

If desired, the several bases of the diamond may be indicated by cutting out the board and arranging transparent or semi-transparent material over the cut-out portions, or said bases might be indicated by coloring.

As, practically, the entire board with the exception of the figures indicated thereon and the transparent or semi-transparent material, hereinafter described, for showing the direction of a batted or thrown ball, is to be of an opaque nature, it will be noted that only the said figures and the said transparent or semi-transparent material will be illuminated when an illuminant is passed along in rear thereof.

In order to obtain the best results in practice, I intend to separate the various figures to a somewhat greater extent than is shown

on the drawings, so that only one figure at a time will be illuminated, thus avoiding the effect of two overlapping illuminated figures.

With a view of still further increasing the interest taken by the spectators, I propose to show a batted ball as moving in various directions, and also while being thrown from one player to another. For attaining these objects any desired construction may be resorted to, but I preferably provide the board 1 with very narrow slots 35 running in the various directions in which a ball might be batted in an actual game. For instance, I show a slot 35 running from the pitcher in the act of pitching a ball, to the catcher in the act of receiving it, and a similar slot 35 running from the catcher in the act of throwing the ball, to the pitcher in the act of catching it. I also show a slot 35 running from the home base to the figure of the pitcher in the act of picking up the ball, and a similar slot running from the pitcher in the act of throwing the ball, to the first baseman.

It will be understood that any desired number of slots may be provided, running in a greater or less number of directions so as to represent as closely as possible the various directions in which a ball may be batted or thrown.

Secured to the outer face of the board 1 over the slots 35 are narrow strips 35' of transparent or semi-transparent material, as mica, through which light from an illuminant at the rear of the board may pass, and as such illuminant is moved along the slot it will indicate graphically a ball moving in the direction corresponding to the slot. The mica sheets 35' might be dispensed with if desired.

Arranged in rear of the board 1 and adjacent thereto is a suitable support, as for instance a board 40 corresponding in size to the board 1, and which like the latter, is preferably constructed of some light and inexpensive material, as wood, paper-board, etc. For the purpose of facilitating the work of the operators of the device, who are to be stationed in rear of the board 40, I propose to provide the rear face of board 40 with the representation of a base-ball diamond, field, players, etc., all to be a counterpart of the showing on the front of board 1, but in reversed position, as seen clearly in Fig. 2.

The board 40 is provided with narrow slots 41 lying directly in rear of the slots 35, and it is also provided with slots 42 which lie in rear of the figures of the players on the front board.

For the purpose of illuminating the figures on the front-board and also to indicate the travel of a batted or thrown ball, whereby the spectators may be enabled to see the various plays as they occur, any suitable

illuminating device may be employed, as for instance small incandescent electric lamps 45 which are adapted to be moved along the various slots 41 and 42. As a lamp is moved along a slot 42 the light will illumine the figures of the players in succession and produce a motion-picture effect, and this effect is heightened the more rapidly the lamp is moved along a slot. Similarly when a lamp is moved along a slot 41 it will indicate a ball as traveling across the field. I preferably arrange each of the lamps within a closed box 46 which is adapted to be moved along within the space intermediate the two boards 1 and 40. I provide each box in front of the lamp therein with, preferably, a ground glass plate 47 inserted in a groove in the box and held firmly in said groove by fitting tightly, or by providing a suitable locking catch if desired. The boxes for indicating the balls are preferably made considerably smaller than the other boxes. By using a closed box for each lamp, I avoid diffusion of the light and cause same to be concentrated upon the ground glass front, whereby I obtain a better illuminating effect.

Inasmuch as I desire to represent a ball in its travel by a very small point of light, I preferably render the ground glass plate in each box intended for use in indicating a moving ball opaque with the exception of just a very small portion in the center of said plate, the light from the lamp therefore passing through the portion left for that purpose.

I preferably represent the players of the two teams by contrasting colors in order to make the game still more interesting and for this purpose the ground glass front of a box would indicate by its white light a player of one team, while by using a colored glass plate inserted in front of the ground glass plate a pair of the other team would be indicated. The colored glass plate, as 50, might be inserted in a groove 51 in the box in front of the ground glass plate 47, and removably held by a suitable locking catch 52, or the plate 50 might be inserted in front of the plate 47 in the same groove that contains the latter. The insertion and removal of the colored plates would, of course, be effected after each half inning has been played.

Each of the boxes containing the illuminant is provided with a suitable handle 55 pivotally connected with the box by which an operator may readily move the boxes along the slots.

For the purpose of maintaining the boxes in their proper positions behind various players which it may be desired to illumine, any suitable means may be employed, as for instance notches 58 joining the grooves at the proper points and into which notches the handles of the boxes may be inserted and

will thus be held from moving accidentally away from their proper positions. The notches may be of different shapes as shown in Figs. 6 and 7.

Instead of using an electric lamp to indicate a ball in motion or to illumine the figures of the players I could use some very light-colored material, as white, which would act as an illuminant and give the same effect as the electric lamp, and such material would be arranged on a suitable support carried by the handle, or secured on the outer face of the ground glass plates of the boxes. I prefer, however, to use the electric lamps for the described purposes.

I provide the rear board 40 at suitable points with openings 60 large enough to permit the ready insertion and withdrawal of the light boxes, as desired, and after a box has been inserted within one of the openings it may be moved along the slot with which the opening communicates. As soon as a box has been inserted within an opening the latter is adapted to be closed by a suitable curtain 61, which would fall over said opening to prevent any light showing through the opening and thus accidentally illuminating any of the figures on the front board.

In practice the boards may be arranged in a vertical position or a more or less inclined position, as desired, an inclined position being preferred to enable the operators to more readily reach the handles of the boxes and enabling handles of less length to be used.

65 indicate narrow strips of very thin and flexible opaque material, as leather or fabric, arranged over the slots 41 and 42, one edge of each of the strips being secured to the face of the board 40, and the opposite free edges of the strips meeting each other over the slot. As a lamp is moved along a slot the strips 65 will separate to permit such movement and close together immediately behind the box thus preventing any light from the rear of the board 40 from gaining access to the space between the two boards and showing through any of the figures on the front board.

Supposing a game to be about to start. The various players in the field and the umpires and coaches will be illuminated by placing the proper light boxes in rear thereof. As the ball is pitched a light box is moved along the slot extending from the figure of the pitcher in the act of pitching the ball, to the figure of the catcher in the act of catching the ball. If the ball is caught by the catcher the light box is switched to a position behind the figure of the catcher in the act of throwing the ball back to the pitcher (or any other player) and at the same time the light box indicating the ball is switched from the catcher in the act of catching it to the figure of the same player

in the act of throwing it. If the ball is returned to the pitcher the light box indicating the ball will be returned along the slot leading to the pitcher in the act of receiving it. If, however, the pitched ball is bunted, 5 for instance, the light box indicating the ball is run along the groove extending from the home base to the pitcher in the act of picking up the bunted ball, and at the same 10 time the light box which was behind the pitcher in the act of pitching the ball is shifted so as to show the pitcher running after the ball and then to a position in rear of the pitcher picking up the ball. Then the 15 box is shifted to the pitcher throwing the ball to the first baseman and at the same time the box indicating the ball is shifted from the pitcher picking up the ball to the pitcher throwing the same and is then further shifted from the last-mentioned figure 20 to the first baseman. In the meantime the batter is represented as running to first base by shifting a light box along the proper slot from home base to first base, thus successively illuminating the figures representing 25 the batter as running to first base. In case the ball is batted to the outfield for instance, then the play by the fielder would be indicated by the shifting of the proper light boxes in a manner similar to that just above 30 described. If the batted ball gives the batter more than one base, then he will be indicated as running to second base, etc. by moving a light box in the proper slot to show 35 the batter as running to the proper base. If a batter is declared out the light box will be shifted along the proper slot showing him returning to the bench, and at the same time the light box behind the first baseman catching 40 the ball will be shifted to the first baseman throwing the ball back to the pitcher. Also, the box indicating the ball will be properly shifted to the first baseman throwing 45 the ball and shifted along the proper groove back to the pitcher.

Numerous plays such as occur in a regularly played game might be readily indicated by proper shifting of the light boxes in the manner hereinabove described, and it 50 is unnecessary to describe herein every such play for a clear understanding of the invention.

What I claim is:

1. A base-ball score-board comprising a 55 board provided with representations of a human figure arranged in succession and adapted to permit light to pass therethrough and having attitudes corresponding to those of a person while in the act of moving from one point to another, and an illuminant adapted to be passed in rear of said representations in succession.

2. A base-ball score-board comprising a 60 board provided with representations of a player in different standing and running po-

sitions, said representations being arranged in proximity to each other and adapted to permit light to pass therethrough, and an illuminant adapted to be moved in rear of said representations for the purpose of indicating the various attitudes of the player. 70

3. A base-ball score-board comprising a board provided with representations of different players and a slot extending from the representation of one player to the representation of another player, means for illuminating said representations, and means adapted to be moved in line with said slot to indicate a ball as being thrown by one player 75 to the other.

4. A base-ball score-board comprising a board provided with representations of a player in different playing positions, a second board arranged in rear of the first and provided with a slot lying in rear of the said representations, and an illuminant adapted to be transferred from a point in the slot behind one representation to another point in said slot behind the other representation for the purpose set forth. 80

5. A base-ball score-board comprising a board provided with representations of players, a second board arranged in rear of the first and provided with slots lying in rear of the representations on the first board, 85 strips of flexible opaque material secured to the said second board over the said slots as described, and an illuminant adapted to be moved along the slots between the meeting edges of the said strips of material as set 90 forth. 100

6. A base-ball score-board comprising a board provided with slots extending in various directions, a second board arranged in rear of the first and provided with slots 105 lying in rear of the slots in the first board, strips of flexible opaque material secured to the second board over the slots therein, and an illuminant adapted to be moved along the latter slots between the meeting edges of the said strips of material as set forth. 110

7. A base-ball score-board comprising a board provided with representations of players, a second board arranged in rear of the first and provided with slots lying in 115 rear of said representations and having openings communicating with said slots, an illuminant adapted to be passed through said openings and to be moved along the slots, and a curtain secured to the second 120 board over each of the said openings for the purpose set forth.

8. A base-ball score-board comprising a board upon which various plays of a game are to be reproduced, a second board arranged in rear of the first and provided with slots, an illuminant, a box within which said illuminant is arranged, said box being arranged in the space between the two boards, 125 strips of flexible opaque material secured to 130

the second board over the said slots, and a handle on the box adapted to extend through the slots between the meeting edges of the said strips.

- 5 9. A base-ball score-board comprising a board provided with a series of representations of a player of one team, said representations being arranged in succession to indicate said player as moving from one point to another, and said board being also provided with representations of two players of the opposing team, means for illuminating in succession the representations of the player of the first-mentioned team, and means for 10 indicating a ball as being thrown by one of the said two players of the opposing team to the other.
- 10 15. A base-ball score-board comprising a board provided with a series of representa-

tions of a player of one team, said representations being arranged in succession to indicate said player as moving from one point to another, and said board being also provided with representations of two players of the opposing team, means for illuminating in succession the representations of the player of the first-mentioned team, and means for indicating a ball as being batted to some point on the field and then being thrown by one of the said two players of the opposing team to the other.

In testimony whereof I affix my signature in presence of two witnesses.

GEORGE S. COLEMAN.
